(57) **CLAIM**

The ornamental design for a firearm slide, as shown and described.

DESCRIPTION

FIG. 1 is a perspective view of a firearm slide showing our new design;

FIG. 2 is an alternate perspective view of the firearm slide of FIG. 1;

FIG. 3 is an elevational view of a breech end of the firearm slide of FIG. 1;

FIG. 4 is an elevational view of a muzzle end of the firearm slide of FIG. 1;

FIG. 5 is a side elevational view of the firearm slide of FIG. 1; FIG. 6 is a top view of the firearm slide of FIG. 1; and, FIG. 7 is a bottom view of the firearm slide of FIG. 1.

The various tones of gray shading on the surface portions indicate contour and not surface decoration.
